UNITED STATES PATENT OFFICE.

GEORGE W. MORROW, OF SAN FRANCISCO, CALIFORNIA, ASSIGNOR TO CLOVERLEAF PROPELLER COMPANY, OF SAN FRANCISCO, CALIFORNIA, A CORPORATION OF CALIFORNIA.

PROPELLER.

Application filed December 27, 1922. Serial No. 609,179.

To all whom it may concern:

Be it known that I, GEORGE W. MORROW, a citizen of the United States, residing in the city and county of San Francisco and 5 State of California, have invented new and useful Improvements in Propellers, of which the following is a specification.

This invention relates to screw propellers for vessels of all classes.

10 The object of the invention is to provide a more efficient design for absorbing power and creating thrust, both in a forward and reverse direction than is possible with the standard designs now in use.

15 This object is accomplished by developing the following edge of each blade forwardly into an easy stream line surface and thereby forming a portion of said blade, which has the effect of releasing the thrust gradually 20 at the following edge and so reducing cavitation and increasing efficiency, particularly in the reverse direction. These blades have a slightly increasing pitch from the hub to the tip, being about 5% less at the hub than

25 at the tip. The tip of the leading edge is curved rearwardly and the tip of the following edge is curved forwardly on a circle of radius approximating 5 inches for all ordinary wheels. The extreme diameter, pitch 30 ratio and surface ratio and number of blades are to be determined in the usual way and to suit the requirements which may be exacted.

35 One form which my invention may assume is exemplified in the following description and illustrated in the accompanying drawings, in which—

Fig. 1 shows a rear elevation of a propeller embodying my invention.

Fig. 2 shows an edge view of the same.

40 Fig. 3 shows a longitudinal section through the hub and one of the blades.

Fig. 4 shows cross sections of the blade on various radii.

45 Fig. 5 shows a cross section of the blade on the lines 1^a to 6^a, inclusive of Fig. 3.

Fig. 6 shows a cross-section of one of the blades, taken on the line 6—6 of Fig. 1.

Fig. 7 shows a perspective view of my propeller.

50 The propeller comprises a hub portion 10 and a plurality of fan-shaped blades 11 disposed helically about the hub. Each blade is composed of two sections 12 and 13 of unequal widths. These sections are curved oppositely in a fore and aft direction, the wid-

er section having its tip curved rearwardly and being effective for forward propulsion, while the narrower one has its tip curved forwardly and is effective for driving astern.

55 Loss of power, due to cavitation, is caused by the formation of vortex spirals produced by the flow of water from the pressure to the suction side near the tip of a propeller blade. By forming each blade in two sections and curving them in the manner 60 shown, the effect of these vortex spirals will be considerably reduced.

65 The pitch of the blades increases axially, being about 5% greater at the outer end than at the hub. The rearward incline or 70 rake usually given to blades may be omitted and the formula for determining the thickness of the blades may be that of the lowest constant of the American Bureau of Shipping. 75

75 The advantage of this design is that the blades concentrate and entrain the water, thereby producing a greater thrust for the same diameter of blade. Vibration is considerably reduced and a much larger amount 80 of power is effectively absorbed in driving astern.

85 The forward driving action of the blade is produced in a large measure by the section 12 which may be considered as being developed along the lines of a standard screw blade. The presence of the section 13 at the rear thereof causes a gradual release of the thrust and the reduction of cavitation, owing to its stream line design. Its rear section will also be effective when the propeller is driven in a reverse direction. Therefore, the present device becomes of considerable advantage in connection with tugs, ferry boats and the like where considerable driving astern is necessary. 90

95 The extreme diameter, pitch ratio, surface ratio and number of blades can be varied as desired and are determinable by any of the standard methods in use for 100 helical screws.

105 The sections of the blade near the tips are hollowed out on the driving faces as shown on the cross section 5^a—5^a of Figure 5, thus affording an easy stream-line surface for the purpose of releasing the waters. The opposite faces of the blade sections near the tips gradually merge or fade together, thus reducing the curvature and increasing the efficiency, particularly in a reverse direction. 110

Having thus described my invention, what I claim and desire to secure by Letters Patent is:

1. A screw propeller, comprising a hub, a plurality of fan-like blades disposed helically about the hub, each blade being bifurcated at its tip, with the bifurcated portions curved oppositely in a fore-and-aft direction adjacent their tips, the portion of the blade adjacent the leading edge being substantially in the form of a standard screw-blade and the portion of the blade adjacent the following edge being curved forwardly and merging gradually into the other portion of the blade whereby to form a stream-line surface for the release of water from contact with the blade.
2. A screw propeller comprising a hub, a plurality of fan-like blades disposed helically about the hub, each blade being com-

posed of two sections of unequal widths and curved in opposite directions.

3. A screw propeller comprising a hub, a plurality of fan-like blades disposed helically about the hub, each blade being composed of two sections of unequal widths, the wider section having its tip curved rearwardly and the narrower section having its tip curved forwardly.

4. A screw propeller comprising a hub, a plurality of fan-like blades disposed helically about the hub, each blade being composed of two sections, the section toward the leading edge being wider than the other section and having its tip curved rearwardly for forward propulsion and the other wing having its tip curved forwardly for driving astern.

GEORGE W. MORROW.
